UNITED STATES PATENT OFFICE

CHARLES E. WARD, OF CHARLESTON, WEST VIRGINIA

SEAL FOR STERN BEARINGS FOR PROPELLER SHAFTS

Application filed September 14, 1927. Serial No. 219,516.

This invention relates to a seal for stern bearings for propeller shafts and has for its object to provide a seal which will be simple in construction and more efficient in operation than those heretofore proposed.

With these and other objects in view the invention consists in the novel details of construction and arrangements of parts which will be more fully hereinafter disclosed and particularly pointed out in the claims.

Referring to the accompanying drawings forming a part of this specification in which like numerals designate like parts in all the views:

Fig. 1 is a diagrammatic sectional view taken longitudinally of a boat adjacent a propeller shaft;

Fig. 2 is a transverse sectional view taken as on the line 2—2 of Fig. 1, and looking in the direction of the arrows; and

Fig. 3 is an enlarged longitudinal sectional view through the stern tube and strut bearing taken as on the line 3—3 of Fig. 2 and looking in the direction of the arrows.

This invention while applicable to boats in general, is more particularly adapted for use with shallow draft vessels of the tunnel or chambered type, having a screw or propeller in each tunnel. With shallow draft vessels there has been a high degree of repair and replacement made necessary due to the fact that the propellers have so churned the water of the shallow rivers on which the boats navigate, that the sand and other hard fine particles of matter on the bottom of the river and in suspension in the water have reached and entered the strut bearings for the propellers, become lodged therein and consequently caused a grinding or wearing away of said bearings. Numerous sealing devices and constructions for preventing this damaging action have been heretofore proposed but, in so far as is at present known, none have been efficient. By this invention the bearings are effectually kept free of abrasive and other foreign matter.

In the drawings 1 indicates a vessel of the shallow draft type provided with a main bottom extending along the major portion of its length, said main bottom as it approaches the

stern rising toward the top of the boat to form the inclined portion 2 of said bottom. This inclined bottom extends upwardly and then inclines downwardly as indicated in said figure to form the tunnel 3 in which the propeller 4 is adapted to rotate. Between the tunnels, which are only sufficiently large to accommodate a propeller, the boat is provided with a subsidiary bottom 5 substantially parallel with the main bottom of the boat, and in Fig. 2 it will be seen that each tunnel is arcuately formed in a transverse plane.

The main propeller shaft indicated at 6 extends through a stuffing box generally indicated at 7 which is associated with the stern tube casting 8 made rigid with the inclined bottom 2 of the vessel, and said shaft 6 extends out of the vessel through a sleeve pipe 9 welded or otherwise secured as at 10 to provide a leak-proof joint with the inclined bottom 2. This sleeve pipe extends rearwardly to the strut casting generally indicated by the numeral 12 which has integrally formed therewith the radial arms 13 and 14 to space the strut casting within the tunnel 3, all as will be readily understood. The arms 13 and 14 are made hollow throughout their length and are joined to the tunnel in such manner as to provide a leak proof joint. Further, the joint between the sleeve pipe 9 and the strut casting 12 is welded or otherwise formed as at 15 to make the same leak-proof.

The propeller shaft 6 extends through the strut casting and has a sleeve 20 thereabout, one end of which extends slightly within the stern end of the sleeve pipe 9 but not in contact therewith. In other words, the shaft sleeve 20 is pressed tightly onto said shaft, or if preferred the shaft may be provided with an enlarged portion of the same shape and size as the sleeve 20, the purpose being to prevent the shaft proper from becoming unduly worn in the strut casting bearing. The sleeve 20 rotates in the strut bearing sleeve shell 22, the usual Babbitt material 23 being interposed therebetween, but the bearing sleeve shell 22 is held in spaced relation, with reference to the strut casting 12 by inwardly extending flanges, such as 24 100

at the forward end of said casting (see Fig. 3) and 25 at the stern thereof, the latter having rigidly associated therewith a plurality of studs 26 arranged circularly thereof and extending outwardly therefrom to which may be secured the strut packing plate 27 as well as the bearing sleeve shell 22. Between the flanges 24 and 25, the hollow casting 12 is provided with a plurality of annular ribs 28 which are drilled as at 29 to provide passages between the compartments formed on either side of said ribs, for a purpose presently to be disclosed. All of the ribs as well as the stern flange 25 are adapted to support the bearing sleeve shell 22 which is provided at its stern end with an outwardly extending flange 30, which in turn is provided with a plurality of holes through which will pass the studs 26. The strut packing plate 27 is similarly apertured to receive the same studs, the surfaces between the packing plate and the flange 30 as well as the surfaces between the flanges 30 and 25 being suitably machined, or fitted with soft gaskets as found necessary or convenient, to make a water tight joint. The plate 27, with the flange 30 of the bearing sleeve shell 22 therebetween, is secured to the casting 12 by nuts 32 which may in turn be locked in any suitable manner as by pins 33 to the studs 26.

The inner surface of the bearing sleeve shell 22 at the stern end, as well as the outer circular surface of the flange 30 thereof is provided with one or more circumferentially extending grooves 35 and 36 respectively, and the boss portion 38 of the strut packing plate 27 likewise has its inner and outer circular surfaces provided with similar circumferentially extending grooves 39 and 40 respectively of which there are a plurality. In practice it has been found advantageous to make the internal diameter of the major portion of the circular boss 38 slightly greater than the external diameter of the shaft sleeve 20, but to have said sleeve somewhat snugly fitted by the packing plate 27 between the flat side thereof and the first circumferential groove on the inner surface of the boss 38, as clearly indicated at 42.

The stern end of the propeller shaft 6 is provided with the usual taper 45 to slidingly fit the propeller hub 46. The forward face 47 of said hub is flat and has extending therefrom a plurality of circularly disposed studs 48 to receive the hub packing plate 50 suitably apertured to receive said studs and held to said hub as by the nuts 51 which may be locked or otherwise made secure as by pins 52. The hub packing plate has forwardly extending thereof a plurality of concentric ribs or flanges, the innermost 53 adapted to overlie the propeller shaft 6 and extending toward but not quite reaching the shaft sleeve 20. The flange 53 as will be readily seen from Fig. 3 extends into the space

formed between the shaft 6 and the inner surface of the boss 38 of the strut packing plate 27. The hub packing plate is also provided with another circular flange 54 extending into the space between the outer surface of said boss 38 and the circular row of nuts 32 holding the strut packing plate to the strut casting. Lastly, there is provided a third circular flange 55 which is adapted to form an outer protective casing about the extreme peripheries of the strut packing plate 27 and the flange 30 of the bearing sleeve shell 22, said flange 55 extending substantially to the strut casting 12, all as clearly indicated in Fig. 3.

At suitable intervals there are provided radial bores such as 60 extending through the babbitt bearing sleeve shell to connect the outer surface of the propeller shaft sleeve 20 with the circular chambers such as 61 in the strut casting, and at least one of these chambers is in open communication with the hollow interior such as 62 of the radial strut spacing arm 13, see Fig. 2. Thus it will be seen that there is provided open communication between the interior of the arm 13 and the propeller shaft sleeve 20, so that any lubricant reaching said sleeve 20 can pass there along and ultimately reach the grooves 35, 39, 40 and 36.

The lubrication of the strut bearing and propeller shaft is accomplished preferably with grease which is slowly but continuously forced under pressure through a conduit 70 to and into one of the strut supporting arms such as 13. The grease will be forced from the chamber 62 thereof into the strut casting chamber 61, thence through the openings 29 into the other chambers of the casting 12, and thence through the passages 60 to the outer surface of the propeller shaft sleeve 20. The grease will then pass along said surface, reaching in one direction the space 71 between the propeller shaft and the pipe sleeve 9 filling the same, and said grease will extend in the opposite direction to enter and fill the circumferential grooves 35 between the shaft sleeve 20 and the bearing sleeve shell 22. There will be a slowing down of the flow of grease at this point due to the joint 42, but the grease being under pressure and the joint 42 not being tight, the grease will pass said joint, enter the grooves 39 and the spaces associated therewith, pass around the end of the boss 38 and enter the grooves 40 on the other side thereof, pass around the end of the flange 54 and completely fill the space between said flange and the outer flange 55, and enter the circumferential groove 36 in the outer end of the flange 30 of the bearing sleeve shell 22, after which the grease is free to escape to the water past the end of the flange 55 of the hub packing plate 50. It is to be understood that all of the spaces just enumerated are filled with grease before the vessel is actually put

into service so that no abrasive material such as sand or the like will be in any of said spaces before the grease is caused to flow through the strut bearing. In this connection it should be stated that the pipe sleeve 9 is also entirely filled with grease which may be fed thereto directly from inside the vessel so that grease under pressure may reach the strut casting 12 from two separate sources, although in the drawings the supply of grease to said pipe sleeve 9 at a point within the vessel is not shown. Such a connection could be made through the packing gland 7 as will be readily understood.

Thus it will be seen by this invention grease or other suitable lubricant is continuously supplied to a point within the strut casting 12 and that said lubricant continually moving toward one outlet only will prevent the admission of any abrasive material such as sand which would have the tendency to grind out the shaft and strut bearings. In other words, this invention covers a stern bearing for a propeller shaft having in combination with said shaft a strut casting, a plurality of intercommunicating chambers 61 and 62 in the casting, the chambers 61 being formed by the annular ribs 28 having apertures therethrough to further aid said intercommunication between the chambers, a bearing sleeve 22 for the shaft provided with passages leading from the chamber 61 to the shaft, said passages being radially formed through the sleeve and said sleeve provided with the angular projection 30 having grooves or passages 35 and 36 circumferentially of said sleeve on the inner and outer surfaces thereof. Also there is provided a packing plate 27 for the strut associated with the sleeve 22 which is likewise provided with grooves or passages 39 and 40, as well as a hub for the shaft and a hub packing plate 50 coacting with the shaft 6 and grooved strut packing plate 27 by virtue of the concentrically disposed flanges 53, 54 and 55. Lastly, the lubricant under pressure is passed through the chambers 61 and 62, the passage 60 of the sleeve 22 past the grooves 35, through the strut packing plate 27 into and out of the grooves or space between the concentric flanges or ribs 53, 54 and 55 of the hub packing plate whereby foreign material having abrasive action is prevented from entering the bearing and wearing the same away through their grinding action. There is a coaction between the hub packing plate 50 and the strut packing plate 27 due to the fact that the former is rigidly associated with the hub 46 which revolves with the propeller shaft, whereas, on the other hand, the strut packing plate 27 is secured to the strut casting 12 which is in turn secured to the hull of the vessel and therefore is stationary. The lubricant, grease, entering and lying within the grooves 35, 36, 39 and 40, and the channels or passages formed between the

flanges 53, 54 and 55 of the hub packing plate will thus always have a moving surface in contact therewith which will cause the grease or other lubricant to be moved in a circumferential plane passing transversely through the propeller shaft, and this coupled with the fact that the lubricant is under continuous forced feed, as well as the tortuous path through which said lubricant moves laterally of the bearing or is moving from one of the chambers 61 of the strut casting 12 to the outlet at the end of the flange 55 of the hub packing plate, will cause a two-fold movement of said lubricant whereby there is produced a washing out of any particles that could by chance enter through said outlet. Should some particles so enter, they would lodge first within the groove, passage, or reservoir 36, and passing this they would lie within the space between the flanges 54 and 55 constituting another reservoir in the hub packing plate. It might barely be possible but highly improbable that said particles would continue to go beyond this passage but should they do so they would collect in the passages 40 of the strut packing plate 27. The passages or grooves 39 and 35 are added by way of extreme caution.

It is obvious that those skilled in the art may vary the details of construction as well as the arrangements of parts without departing from the spirit of the invention, and therefore it is not desired to be limited to the foregoing disclosure except as may be required by the claims.

What is claimed is:—

1. In a stern support for a propeller shaft in combination with said shaft a sleeve therefor; a packing plate provided with a circular boss in prolongation of said sleeve; a strut casting encasing said sleeve and to which said plate and sleeve are secured; a hub for said shaft provided with a packing plate having on one face thereof a channel telescoping said boss; and lubricant filled corrugations on said boss as well as on said sleeve.

2. In a stern support for a propeller shaft in combination with said shaft a fixed sleeve therefor; a packing plate associated therewith and provided with a circular boss extending around said shaft said boss having a plurality of open corrugations to receive and retain lubricant; and a hub for said shaft provided with a packing plate having on one face thereof a channel closely confining said boss.

3. In a stern support for a propeller shaft in combination with said shaft a sleeve therefor provided with lubricant filled corrugations on its shaft side; a packing plate concentric with said shaft and provided with a flange coextensive with said sleeve, the opposite faces of said flange having parallelly disposed lubricant filled grooves; a strut casting constituting a lubricant reservoir, said

casting encasing said sleeve and supporting said plate; and a hub for said shaft provided with a packing plate provided with a channel into which said flange extends.

- 5 4. In a stern support for a propeller shaft in combination with said shaft a sleeve therefor provided with lubricant filled corrugations on its shaft side and further provided with an angular extension having in its extremity a lubricant filled groove; a packing plate concentric with said shaft and provided with a flange coextensive with said sleeve, the opposite faces of said flange having parallelly disposed lubricant filled grooves; a strut
- 10 15 casting constituting a lubricant reservoir, said casting encasing said sleeve and supporting said plate through said extension; and a hub for said shaft provided with a packing plate provided with plural channels into one of which said flange extends and the other of which closely confines said extension and its groove.

- 20 5. In a bearing for a shaft provided with a hub the combination of a hub packing plate provided with a channel on one face thereof; a sleeve on the shaft and provided with a flange at one end thereof; a second packing plate secured to said flange and provided with a boss encircling the shaft, said boss disposed within said channel; and lubricant retaining corrugations on said boss.

- 25 35 6. In a bearing for a shaft provided with a hub the combination of a hub packing plate provided with an inner and an outer channel on one face thereof; a sleeve on the shaft and provided with a flange at one end thereof said flange extending into the outer channel and provided with a lubricant retaining groove cooperating with one side of said channel to establish a bearing seal; a second packing plate secured to said flange and provided with a boss encircling the shaft, said boss disposed within and closely confined by the sides of the inner channel; and lubricant retaining
- 40 45 corrugations on said boss.

In testimony whereof I affix my signature.
CHARLES E. WARD.
